UNITED STATES PATENT OFFICE.

VAUGHN D. MULKEY, OF OAKLAND, CALIFORNIA.

MATTRESS.

Application filed May 14, 1924. Serial No. 713,129.

My invention is an improved mattress. One object of my invention is to provide a cover to completely envelope a mattress, and also to retain the mattress, which is tufted, in shape, so that even if the tufting threads break, the mattress will not come out of shape.

Another object is to provide handles on the mattress which consist of strips completely encircling same.

In the annexed drawing in which my invention is illustrated:

Figure 1 is a perspective view of my mattress.

Figure 2 is an enlarged fragmentary sectional view taken on the line 2—2 of Fig. 1.

Referring more particularly to the drawing, my mattress consists of the usual ticking 1, tufted in the usual manner, and filled with a suitable resilient padding material. A covering sack 2 of any suitable material, and cut to the exact size of the finished mattress envelopes the mattress. The edges of the ticking 1 are not finished until after the cover 2 is in place.

The cover 2 and edges of the ticking 1 are stitched together and form the usual rolled edge 3. The cover 2 extends smoothly over the mattress, and materially adds to the sanitary appearance thereof, as well as to hold it in shape so that it cannot spread laterally.

Cloth strips 4 and 5 extend around the mattress under the cover 2, and protrude from the sides of said cover through slots 6—6 to form handles 7—7 and 8—8. It will be seen that when the mattress is pulled by the handles no strain is placed on the ticking.

Having described my invention, I claim:

A mattress comprising a stuffed ticking, a tight fitting cover secured over said ticking, strips encircling said ticking under the cover and fastened to said cover at the edges only, said cover having slots formed therein through which the strips protrude to form handles.

In testimony whereof I affix my signature.

VAUGHN D. MULKEY.
